United States Patent Office

Des. 206,459
Patented Dec. 13, 1966

206,459

PORTABLE POWER-DRIVEN TOOL

Harper Landell, Fort Washington, Pa., and Thomas C. Abrahamsen, Haddonfield, N.J., assignors to The Black and Decker Manufacturing Company, Towson, Maryland, a corporation of Maryland

Filed May 11, 1966, Ser. No. 2,256

Term of patent 14 years

(Cl. D54—14)

FIG. 1

FIG. 2

FIG. 3

FIG. 4FIG. 5FIG. 6FIGURE 1 is a top plan view of a portable power-driven tool embodying our design;

FIGURE 2 is a side elevation;

FIGURE 3 is a bottom plan view;

FIGURE 4 is a perspective;

FIGURE 5 is a front elevation; and

FIGURE 6 is a rear elevation.

The dominant features of our design reside in the portions shown in full lines.

We claim:

The ornamental design for a portable power-driven tool, as shown and described.
